US00D948459S

(12) **United States Design Patent** (10) Patent No.: **US D948,459 S**
(45) Date of Patent: **** Apr. 12, 2022**

(54) **CIRCUIT BREAKER**

(71) Applicant: **ABB S.P.A.**, Milan (IT)

(72) Inventors: **Lucio Azzola**, Bergamo (IT); **Giovanni Frassineti**, Bergamo (IT)

(73) Assignee: **ABB Service S.R.L.**, Milan (IT)

(**) Term: **15 Years**

(21) Appl. No.: **29/698,028**

(22) Filed: **Jul. 12, 2019**

Related U.S. Application Data

(62) Division of application No. 29/622,244, filed on Oct. 16, 2017, now abandoned, which is a division of application No. 29/558,155, filed on Mar. 15, 2016, now Pat. No. Des. 803,166, which is a division of application No. 29/484,272, filed on Mar. 7, 2014, now Pat. No. Des. 755,131, which is a division of application No. 29/416,701, filed on Mar. 26, 2012, now Pat. No. Des. 703,621, which is a division of application No. 29/356,421, filed on Feb. 25, 2010, now Pat. No. Des. 660,805, which is a division of application No. 29/331,873, filed on Feb. 3, 2009, now Pat. No. Des. 611,002, which is a division of application No. 29/241,662, filed on Oct. 31, 2005, now Pat. No. Des. 587,658.

(57) **CLAIM**

The ornamental design for a "circuit breaker", as shown and described.

DESCRIPTION

FIG. 1 is a perspective view of a circuit breaker;

FIG. 2 is a front view of a circuit breaker;

FIG. 3 is a right view of a circuit breaker;

FIG. 4 is a left view of a circuit breaker;

FIG. 5 is a bottom view of a circuit breaker;

FIG. 6 is a top view of a circuit breaker; and,

FIG. 7 is a rear view of a circuit breaker.

Broken lines in the drawings form no part of the design to be patented.

1 Claim, 7 Drawing Sheets
